(57) **CLAIM**
The ornamental design for a ceiling-mounted monitor system, as shown and described.

DESCRIPTION

FIG. 1 is an inverted, front perspective view of the design of the invention, with the panel-component in the deployed position ("the Deployed Position").

FIG. 2 is an inverted, back perspective view of the design of the invention, with the panel-component in the Deployed Position.

FIG. 3 is an inverted, front perspective view of the design of the invention, with the panel-component in the stowed position ("the Stowed Position"); and,

FIG. 4 is an inverted, back perspective view of the design of the invention, with the panel-component in the Stowed Position.

The broken line(s) shown in the drawings are for illustrative purposes only and form no part of the claimed design.

The bottom of the design is flat and unornamented, so the bottom view has been omitted.

The stippling and shading lines shown in the drawings represent the approximate three-dimensional contour of the design, and are not intended to indicate surface decoration. Environment is shown by evenly spaced dash-double-dot-broken lines.

Portions of the ceiling-mounted monitor system that are not shown in the drawing(s) form no part of the claimed design.

1 Claim, 4 Drawing Sheets
